(57) **CLAIM**

Applicant claims the ornamental design for a chaise, as shown and described.

DESCRIPTION

FIG. 1 is a front upper perspective view of a first embodiment of a chaise of Applicant's design;

FIG. 2 is a first side elevational view thereof;

FIG. 3 is a second side elevational view thereof, the second side elevational view being opposite the first side elevational view;

FIG. 4 is a front elevational view thereof;

FIG. 5 is a rear elevational view thereof;

FIG. 6 is a top plan view thereof;

FIG. 7 is a bottom plan view thereof;

FIG. 8 is a front upper perspective view of a second embodiment of a chaise of Applicant's design, the second embodiment being a mirror image of the first embodiment;

FIG. 9 is a first side elevational view thereof;

FIG. 10 is a second side elevational view thereof, the second side elevational view being opposite the first side elevational view;

FIG. 11 is a front elevational view thereof;

FIG. 12 is a rear elevational view thereof;

FIG. 13 is a top plan view thereof; and,

FIG. 14 is a bottom plan view thereof.

Where included, broken lines showing environment or structure are for illustrative purposes only and form no part of the claimed design.

1 Claim, 12 Drawing Sheets
